UNITED STATES PATENT OFFICE.

JOHN F. TRITTLE, OF SCHENECTADY, NEW YORK, ASSIGNOR TO GENERAL ELECTRIC COMPANY, A CORPORATION OF NEW YORK.

SELECTIVE A.C.-D.C. SYSTEM.

935,069.

Specification of Letters Patent. Patented Sept. 28, 1909.

Application filed January 18, 1908. Serial No. 411,452.

To all whom it may concern:

Be it known that I, JOHN F. TRITTLE, a citizen of the United States, residing at Schenectady, county of Schenectady, State of New York, have invented certain new and useful Improvements in Selective A.C.-D.C. Systems, of which the following is a specification.

In electrically driven cars intended for 10 operation either on alternating or direct current, usually high potential alternating current and low potential direct current, the change from one to the other being ordinarily made while the car is moving, it is customary to provide a system of selective switches arranged to automatically connect the current collecting device to the proper circuits of the car for either alternating or direct current operation. Such a system of 15 selective switches is shown in the patent to Frank and Pevear, No. 854730, dated May 28, 1907, Control of electric cars. The arrangement there shown consists of a small step-down transformer, having its primary connected 20 to the power circuit, the actuating coil of the A.C. switch being connected across the secondary of said transformer, and the actuating coil of the D.C. switch being in series with the primary of said transformer. With this arrangement the A.C. 25 switch is operated only when the current collecting device is receiving alternating current, and the D.C. switch is supposed to operate only when the current collecting device connects with a source of direct current.

It is found in actual practice that a system such as that mentioned above is open to the objection that when the car enters an alternating current section the first rush of 30 current, before the counter E. M. F. of the transformer has had time to build up, may operate the D.C. switch. Such an occurrence is, of course, highly objectionable, and it is an object of my invention to provide 35 means for absolutely and certainly preventing the D.C. switch from operating when the car enters, or while it is on, an alternating current section.

To the above end my invention consists 40 in providing a slow acting relay, the actuating coil of which is in series with the primary of the transformer and the actuating coil of the D.C. switch. Said relay has contacts which, when the relay is in its deenergized position, complete a circuit through a

non-inductive resistance in shunt to the actuating coils of the relay and the D.C. switch. Said relay also carries contacts which, when the relay is in its deenergized position, complete a circuit in shunt to the whole or a 60 part of the actuating coil of the D.C. switch.

My invention will be more clearly understood from the following description taken in connection with the accompanying drawing, in which I have shown diagrammatically one form in which it may be embodied. I deem it unnecessary to illustrate in connection with my invention any system of motor control, as it is obvious that my invention is altogether independent of any particular control system. I may, however, state that, as illustrated, my selective A.C.-D.C. system is applicable to the system of control set forth in a patent issued in the name of George H. Hill, No. 904,780, dated November 24, 1908.

Referring to the drawing, L represents the trolley wire or other supply conductor with which the trolley T or other current collecting device carried by the car engages. It is to be assumed that the supply conductor is at some places supplied with alternating, and at other places with direct current, the potential of the alternating current section being usually high, for example, 6600 volts, 80 and the potential of the direct current section being relatively low, for example, 600 volts.

The usual kicking coil and lightning arrester are indicated in a well-known conventional manner at A.

The main switch which is intended to close only on alternating current operation is indicated at S, and the main switch which closes only on direct current operation is shown at S¹. These switches S and S¹ may be of any suitable design.

A small step-down transformer represented at E has its primary connected between trolley and ground. The actuating coil 1 of the A.C. switch S is connected across the secondary of the transformer E, and the actuating coil 2 of the D.C. switch S¹ is connected in series with the primary of the transformer E.

A relay M is arranged with its actuating coil 3 in series with the actuating coil 2 of the switch S¹. This relay is retarded in its upward movement by a dash pot 4 which, however, does not interfere with its falling

quickly when the actuating coil 3 is deenergized. The relay M controls two sets of contacts, one of which, 5, completes a circuit to ground through the non-inductive resistance 6 in shunt to the actuating coils 3 and 2 of the relay M and the switch S¹, while the other 7 connects some point 8 on the coil 2 to ground, thereby shunting more or less of the coil 2 of the switch S¹.

10 A contact 9, controlled by the A.C. switch S, is arranged to cut an inductive resistance 10 into circuit with the coil 1 so as to reduce the current flow in this coil after the switch S has closed. Similarly, a contact 11, controlled by the switch S¹, cuts into circuit with the coil 2 a resistance 12 which serves to reduce the current in the coil 2 after the switch S¹ has closed.

15 The operation of my selective system is as follows: Suppose the switches S and S¹ and the relay M to be in the positions illustrated, which are those which they assume when no current is passing to the collecting device. If the collecting device is now caused to engage with a section of trolley wire or third rail carrying alternating current at high potential, current will flow through the primary of the transformer E, through the non-inductive resistance 6, contact 5 of the relay M to ground. The resistance 6 being non-inductive will offer but little hindrance to the flow of the alternating current and most of it will pass to ground by this path. The first sudden rush of current before the counter E. M. F. of the transformer E has had time to build up may be excessive and some current may flow through the actuating coil of the relay M and the actuating coil 2 of the switch S¹. The portion of the 20 actuating coil 2 below the point 8 will, however, receive practically no current, since it is shunted by the wire which connects the point 8 to ground through the contact 7 on the relay M, and the point 8 on the coil 2 is so chosen that the current flowing through the upper part of the coil 2 at this time is insufficient to operate the switch S¹. If the point 8 is suitably located intermediate the ends of the coil 2, the magnetic field 25 produced by the upper part of the coil 2 may be wiped out by the opposing field produced by the lower part of the coil 2 which is short-circuited through ground and which, therefore, acts as the secondary of a transformer of which the upper part of the coil 2 is the primary. The relay M will not operate on this sudden rush of current owing to the retarding effect of the dash pot 4. As the counter E. M. F. of the transformer 30 E soon builds up, the current passing through its primary quickly dies down and practically all of it passes to ground through the non-inductive resistance 6, owing to the reactance of the coils 3 and 2. At the same time the current induced in the secondary

of the transformer E passes through the actuating coil 1 of the switch S and causes this switch to close. The closing of the switch S opens the contact 9 and breaks the short circuit around the inductive resistance 10 thereby causing a cutting down of the current flowing in the actuating coil 1, the current needed to hold the switch S closed being much less than that required to close it. 79

80 If, on the other hand, the collecting device T is connected to a source of direct current, current will pass through the primary of the transformer E, through the coil 3 and the upper part of the coil 2 to the point 8 and to ground, through the contact 7. The resistance 6 will effectively prevent any great amount of current from passing to ground through the contact 5. Under this condition the energization of the coil 2 of the switch S¹ will be insufficient to operate this switch, but the current passing through the coil 3 will be enough to cause the relay M to pull up, an operation which will, however, be impeded by the dash pot 4. As soon as the contact 7 opens, the shunt circuit from the point 8 is interrupted, and the current passing through the coil 3 must pass through the whole of the coil 2 to ground. The excitation of the coil 2 is now sufficient to cause the switch S¹ to operate and it closes. After the main contacts on the switch S¹ have closed, the short circuit around the resistance 12 is interrupted at the contact 11, and the current passing through the primary of the transformer E, the coil 3 and the coil 2 is cut down and heating of these coils thereby avoided. When the contact 5 opens, the circuit to ground through the non-inductive resistance 6 is interrupted and all of the current must flow through the coils 3 and 2. 95

100 While I have shown but one form in which my selective A.C.-D.C. system may be embodied, I wish it understood that I do not mean to confine myself to this particular arrangement, but that I aim to cover all such modifications as will occur to those skilled in this art and are within the scope of my invention. 110

115 What I claim as new and desire to secure by Letters Patent of the United States, is,—

1. A selective A.C.-D.C. system for electric cars comprising a transformer having its primary connected to the power circuit, an A.C. switch, an actuating coil therefor connected to the secondary of said transformer, a D.C. switch, an actuating coil therefor connected to the power circuit through the primary of said transformer, a slow acting relay having its actuating coil arranged in series with the primary of said transformer and the actuating coil of said D.C. switch, a shunt circuit containing a non-inductive resistance around the actuating coil of said relay and the actuating coil 125 130

- of the D.C. switch, and contacts controlled by said relay when it is in its deënergized position for shunting more or less of the actuating coil of the D.C. switch.
- 5 2. A selective A.C.-D.C. system for electric cars comprising a transformer having its primary connected to the power circuit, an A.C. switch, an actuating coil therefor connected to the secondary of said transformer, a D.C. switch, an actuating coil therefor in series with the primary of said transformer, a slow acting relay having its actuating coil in series with the primary of said transformer and the actuating coil of 10 said D.C. switch, a non-inductive resistance, contacts controlled by said relay and closed when said relay is in its deënergized position for shunting the actuating coils of the relay and the D.C. switch through said non-inductive resistance, and other contacts controlled by said relay also closed when said relay is in its deënergized position for shunting more or less of the actuating coil of the D.C. switch.
- 20 25 3. A selective A.C.-D.C. system for electric cars comprising a transformer having its primary connected to the power circuit,

an A.C. switch, an actuating coil therefor connected to the secondary of said transformer, a D.C. switch, an actuating coil 30 therefor in series with the primary of said transformer, a relay having its actuating coil in series with the primary of said transformer and the actuating coil of said D.C. switch, a non-inductive resistance, contacts 35 controlled by said relay closed when the relay is in its deënergized position for shunting the actuating coils of the relay and the D.C. switch through said non-inductive resistance, other contacts controlled by said relay also closed when said relay is in its deënergized position for shunting more or less of the actuating coil of the D.C. switch, and means for rendering the relay slow acting 40 in its opening of the contacts controlled by it 45 without interfering with the quick closing of said contacts when the actuating coil of the relay is deënergized.

In witness whereof, I have hereunto set my hand this 16th day of January, 1908.

JOHN F. TRITLE.
